Specification of Letters Patent.

Patented Sept. 9, 1913.

Application filed March 4, 1907. Serial No. 360,379.

To all whom it may concern:

Be it known that I, ANTHONY R. SILVERSTON, a citizen of the United States, residing at Milwaukee, in the county of Milwaukee and State of Wisconsin, have invented 5 certain new and useful Improvements in Airships, of which the following is a specification.

This invention relates to improvements 10 in air ships, and the primary object of the invention is to provide an improved dirigible air ship which is at all times under the control of the operator.

A further object is to provide improved 15 means for propelling or advancing the machine regardless of the direction of the outside air currents.

A further object is to provide improved means for causing an upward or downward 20 flight of the machine.

A further object is to provide an improved aeroplane attachment and improved means for controlling or adjusting the same.

A further object is to provide an improved 25 device of this character which will be simple, cheap and durable in construction and effective and efficient in operation.

To the attainment of these ends, and the accomplishment of other new and useful objects as will appear, the invention consists 30 in the features of novelty in the construction, combination and arrangement of the several parts hereinafter more fully described and claimed and shown in the accompanying drawings, in which:

Figure 1 is a longitudinal sectional view of an improved air ship constructed in accordance with the principles of this invention. Fig. 2 is a front end elevation of Fig. 40 1. Fig. 3 is a rear end elevation of Fig. 1. Fig. 4 is a longitudinal side elevation of a modified form of air ship, with an improved form of aeroplane attachment. Fig. 5 is a side elevation of another form of the invention, with a modified form of aeroplane attachment. Fig. 6 is a sectional view on line 6—6 of Fig. 4. Fig. 7 is a detailed sectional view similar to Fig. 6, showing the aeroplane in an adjusted position. Fig. 8 is a detailed top plan view of Fig. 4. Fig. 9 is a detailed top plan view of Fig. 5, showing the aeroplane adjusted. Fig. 10 is a transverse sectional view on line 10—10 of Fig. 9. Fig. 11 is a detailed sectional view 50 55 of one of the supporting legs.

Referring more particularly to the drawings, the same reference numerals designate similar parts throughout these several exemplifications of the invention, and the numeral 20 designates a tubular body portion, 60 preferably cylindrical in cross section, of any desired size and constructed of any suitable material, such as metal or the like. The forward end of the tubular body portion 20 is preferably flared or enlarged as at 21, to 65 produce a funnel shaped end, and the walls of said flared end are so disposed as to the body portion 20 and the diameter of the latter is such as to form a direct passage for the air through the body portion, regardless 70 of the position or angle of deflection of the said body as shown more clearly by the dotted lines indicated by the reference numeral A, in Fig. 1 of the drawings. The length of the uniform portion of the body 75 20 beyond the flared end 21 is preferably such that the air currents entering the flared end and following the walls diametrically opposite each other would meet each other at a point substantially intermediate the 80 length of the uniform portion 20 of the body. This body portion, together with the flared extremity 21, is open at both ends, and any suitable means may be provided and located within the tubular portion to 85 draw the air into the forward or enlarged end of the body and discharge the same through the rear end thereof. A suitable and efficient means for accomplishing this purpose comprises a propeller of any desired construction, preferably in the shape of a fan 22, which is provided with radially projecting wings or blades, and the diameter of said fan or propeller 22 is of a size slightly less than the diameter of the body 90 portion 20, so that the fan or propeller will substantially fill or extend across the body portion without interfering with the rotation thereof. This fan or propeller is preferably secured for rotation upon a suitable 95 shaft 23, which extends longitudinally through the body portion, and is journaled in suitable bearings 24, which are located, preferably adjacent the diametric center of the said body portion.

The body portion may be suitably braced in any desired manner, but a simple and efficient means comprises a plurality of encircling rings 25, and these rings are located preferably adjacent the ends and also 100 105 110

intermediate the length of the body 20, and are connected or secured together preferably by means of suitable tie rods or bolts 26, and serve as a means for preventing the body portion from collapsing or buckling.

5 A suitable car 27 is suspended from the body portion 20 by means of suitable supports 28, which are preferably connected to the rings 25, and located within the car is 70 a suitable power device 29 for imparting motion to the shaft 23 to rotate the fan or propeller 22. Any suitable means may be provided for this purpose, such as a flexible belt or member 30, which connects the 10 power device 29 with the shaft 23.

15 Located adjacent, and extending across the inlet end of the body portion, and standing preferably in a vertical plane, is a rudder 31. Depending from this rudder is a 20 suitable bar or rod 32, to the free extremity of which is secured a suitable cross bar or arms 33, and connected to the ends of this cross bar or arms 33 are flexible members 34, which are adapted to be wound upon a 25 drum 35 located within the car 27, and said drum is provided with a tiller wheel 36 for rotating the drum, and when said drum is rotated the flexible members 34 will be respectively wound or unwound so as to rock 30 the rudder 33 to deflect the machine.

35 The shaft 23 preferably projects beyond the forward end of the body portion and terminates in advance of the rudder 31, and secured to the free extremity of said shaft is a suitable fan or propeller 37, which is of any suitable size and diameter, and said fan or propeller 37 assists in propelling the machine in a manner to be hereinafter more fully set forth.

40 Pivottally secured by one end, in any suitable manner, and adjacent the discharge or outlet end of the body portion, are a pair of deflectors or members 38, which are preferably spaced from and parallel with each 45 other, one of which is preferably located adjacent the top, and the other adjacent the bottom of the body portion, and said deflectors or members are preferably of a size to extend across the end and project for 50 some distance beyond the body portion, and in a direction transverse to the rudder 31. These deflectors or members 38 may be constructed of any suitable material and are preferably connected at their sides by suitable 55 flexible members 39, so as to form a tubular pivoted portion adjacent the end of the body portion which is open at its free end, and through which the air passes after being discharged from the body portion. These deflectors or members 38 are 60 adapted to be moved about their points of pivotal support to the position shown in dotted lines in Fig. 1 of the drawings so as to direct the air current upwardly, which 65 will tend to raise the front end of the body

and cause the machine to ascend, or they may be deflected in an opposite direction when the machine is in mid air so as to discharge the air downwardly which would deflect the front end of the body downwardly to cause the machine to descend when the motor is in operation. Any suitable means may be provided for controlling or adjusting these deflectors or members 38. A simple and efficient means for accomplishing this purpose comprises a bar or rod 40, one end of which is pivotally secured, as at 41, to the upper deflector or member 38, and also is connected with the lower member as at 42. A suitable bar or 70 rod 43 may be pivotally connected at one end to the body portion 20, as at 44, and pivotally connected as at 45 to the bar or rod 40. The lower extremity of the bar or rod 40 terminates preferably adjacent the car 27, and may be bodily raised or lowered by means of a suitable bell-crank lever 46, one end of which is connected to the bar or rod 40, and connected to the free end of said bell-crank lever 46 is a flexible member 47, which is adapted to be wound upon a suitable drum controlled by a tiller wheel 48. When the drum is rotated by the tiller wheel 48 the bell-crank lever 46 will be moved about its point of pivotal support as 80 shown in dotted lines in Fig. 1 to move the deflectors or members 38 to the position as shown in dotted lines in Fig. 1 of the drawing.

85 In the exemplification of the invention 100 shown in Figs. 1 to 3 of the drawings a suitable gas bag 49 surrounds and is secured to the body portion 20, and passing through said gas bag is a flexible tubular member 50, which is adapted to be threaded 105 on to the body portion 20, and said tubular portion also serves as a means to prevent the escape of the fluid. The gas bag is preferably provided with a pocket 51, through 110 which the flexible member or belt 30 passes and said pocket also serves as a means to permit one of the supports 28 for the car 27 to be secured to the body portion 20 intermediate the ends of the latter.

115 In the exemplification of the invention shown in Figs. 4 to 10 of the drawings suitable improved aeroplanes are provided instead of the gas bag 49, and in the exemplification shown in Figs. 4 and 6 to 8 the improved aeroplane comprises a flexible body portion comprising two members 52 which are pivotally connected by one end, as at 53. The extremities of these body portions 52 are laterally deflected as at 54, in opposite directions, and said deflected portions are 120 disposed on a longitudinal oblique line, extending preferably from a point adjacent the point of junction of the body portion 20 with the flared extremity 21 toward the 125 rear and above the top of the body portion 130

21. This aeroplane is mounted for pivotal movement on the top of the body portion 20, in any suitable manner, such as by means of pivots on the extremity of the same journaled in suitable bearings on the body portion, so that when the machine is in mid air, and the currents of air should strike the machine transversely of the body portion, the said aeroplane will be moved bodily about its point of pivotal support with the body to prevent the machine from being blown over. Any suitable means may be provided for holding the aeroplane in its normal position, but a simple and efficient means for accomplishing this purpose comprises a suitable number of weighted arms or balancing rods 53^a which project laterally from the sides of the aeroplane and extend to a point below the diametric center of the tubular body portion 20, and said arms tend to maintain the equilibrium of the aeroplane. This improved form of aeroplane is adapted to be expanded or opened to the position as shown in Fig. 7 of the drawing, by means of suitable flexible members 55, to increase the surface of the planes to allow a parachute action, one end of which is secured to the body portions 52 of the aeroplane, and the other extremities are adapted to pass around a suitable drum in the car, which latter is adapted to be rotated by a tiller wheel 56, so that when the drum is rotated the flexible members will be wound upon the drum and draw the body portions 52 of the aeroplane apart on their points of pivotal support. The body portions 52 of this aeroplane are adapted to be held normally in contact with each other, and in the position shown in Fig. 6 of the drawing, in any suitable manner, preferably by means of a suitable spring 57 against the tension of which the body portions 52 are moved when the aeroplane is spread, as shown in Fig. 7, and when the flexible members 55 are wound from the drums the spring 57 will serve to return the body portions 52 to their normal position. Suitable guides 58 may be provided which are preferably secured to the body portion 20 through which the flexible members 55 are adapted to pass to permit an easy movement of said members, and when the aeroplane is adjusted or spread the extremities thereof will project laterally beyond the sides and adjacent the top of the main body portion 20.

In the exemplification shown in Figs. 5, 9 and 10 of the drawing the aeroplane comprises two adjustable folding sections 59, which are pivotally supported by the main body portion 20, and extend substantially the entire length thereof and are counterbalanced by the weighted arms 59^a as in the other forms of the invention. These aeroplanes are preferably located above the diametric center of the body portion 21, and

spaced from each other, and preferably projected laterally from the opposite sides thereof upwardly and in an inclined direction, as shown more clearly in Fig. 10 of the drawing. The sections constituting the aeroplanes 59 are pivoted as at 60, preferably adjacent the forward end of the body portion, and said aeroplanes are adapted to be spread in any suitable manner, preferably by means of flexible members or cords 61, which are secured, respectively, by one end to the outer section of the aeroplane, and pass through the ends of a suitable guide 62, which extends transversely across the body portion 20, and is located adjacent the pivoted ends 60. The free extremities of these flexible members 61 are adapted to be wound upon a suitable drum located within the car, and which is controlled by a tiller wheel 63, so that when the tiller wheel is operated to rotate the drum the flexible members 61 will be wound thereon to spread the aeroplanes into the position shown in Figs. 9 and 10.

Any suitable means may be provided for folding or returning the aeroplanes to their normal position, that is, so that the aeroplanes rest closely against the side of the body portion 20. A suitable and efficient means for accomplishing this purpose comprises a spring 64, against the tension of which the sections of the aeroplane are adjusted when the aeroplane is spread.

Any suitable means may be provided for supporting the machine to permit it to move upon the surface of the ground when desired. A simple and efficient means for accomplishing this purpose comprises a series of legs, which are preferably constructed of telescoping sections 65—66. The sections 65 may be pivotally secured to the body portion in any suitable manner, preferably to the rings 25 by one end thereof, and the free extremities of these sections are adapted to enter the tubular sections 66, within which are located suitable cushion devices, such as springs 67 or the like to take up the jar of the machine when the wheels 68, which are rotatably mounted on the free ends of the sections 66, strike the ground on the descent of the machine. Suitable braces 69 may also be provided for the legs. These legs are of a suitable length so that the wheels will extend below the bottom of the car to support the car out of contact with the surface of the ground, and their angle of inclination from the body portion 20 is such that they will not interfere with any of the operating parts of the machine or extend to form projections beyond the sides of the car.

In operation, when it is desired to propel the machine, the fan or propeller 22 is rotated at a greater rate of speed than the speed of the outside air currents, and to a

rate of speed as much in excess of the speed of the outside air as it is desired that the machine shall travel when in flight and in mid air. A rotation of this fan or propeller 5 22 will suck the outside air into the enlarged extremity 21 by normally tending to create a vacuum therein, and when the outside air currents have passed into the machine and beyond the longitudinal center thereof, at 10 which point the fan or propeller is located, so as to permit a free passage of the air therethrough, no matter at what angle of inclination the body portion 20 may be disposed, it will be discharged through the 15 other end of the body at a greater rate of speed than the speed of the outside air, thus causing the machine to advance, and by increasing or decreasing the rate of speed of the fan or propeller 22 the speed of travel 20 of the machine may be increased or decreased. The propeller thus being in operation the machine will travel upon a straight or substantially straight line, and if provided with the supporting wheels 68 25 the machine will travel on the surface of the ground. In order to raise the machine to mid-air the operator simply rotates the tiller wheel 48, which will adjust the deflectors or members 38 about their points 30 of pivotal support, and by raising the free extremities of these members or deflectors to the position shown in dotted lines in Fig. 1 the current of air discharged through the rear of the body will be deflected upwardly, 35 which will cause the forward or enlarged end 21 of the body to be deflected upwardly, and as the air is drawn into the body portion by the fan the suction created thereby will cause the machine to "climb" or be sucked 40 upwardly until the desired height is reached, after which the operator may then adjust the deflectors or members 38 to the position as shown more clearly in full lines in Fig. 1 of the drawing, which will discharge the air 45 to the rear of the machine in a substantially straight line, causing the ship to travel in the plane thus assumed until the members or deflectors 38 are again adjusted and will be maintained or suspended in midair by 50 the current of air passing therethrough. Obviously, when it is desired to make a descent the deflectors or members 38 will be adjusted in the opposite direction, or to a position opposite to that shown in dotted 55 lines in Fig. 1 of the drawings. During the flight of the machine it may be deflected so as to change its course of travel by means of the rudder 31, which is controlled by the tiller wheel 36, the slot 31^a in the rudder 60 permitting the latter to be freely adjusted about its points of pivotal support to assume any angle of deflection with relation to the body portion 20.

The fan or propeller 37, which is located 65 in advance of the rudder 31, being opera-

tively related to the fan or propeller 22, will rotate at the same rate of speed and will materially assist in propelling the machine, as this latter fan or propeller not only has a tendency to draw the machine forward by its suction on the outside air, but also serves to direct the air into the enlarged end 21 of the body portion 20. If desired, this latter fan or propeller may be dispensed with and the machine will be propelled solely by the fan or propeller 22. It will thus be seen that no matter at what rate of speed the outside air is moving the machine will advance at any desired rate of speed against the outside air currents so long as the propeller or fan 22 is rotated at a greater rate of speed than the air currents. The air discharged through the rear end of the machine will strike or brace against the body of the outside air, respectively to which the machine is moving at a slower rate of speed, and advance or progress the machine. 70 75 80 85 90 95 100

In the exemplification shown in Figs. 4 to 10 of the drawing the aeroplanes serve to maintain the machine in mid-air and may be adjusted in the manner already described so as to permit the machine to gradually descend, and said aeroplanes being supported for pivotal movement with relation to the main body portion and counterbalanced to maintain their equilibrium, will assume a proper position with relation to the body portion so as to prevent the machine from being seriously affected by a sudden change in the air currents which might strike the machine from the side or at a right angle to its course of travel. 105

In order that the invention might be fully understood by those skilled in the art, the details of the foregoing embodiments thereof have been thus specifically described, but 105

What I claim as new and desire to secure by Letters Patent is:

1. In combination in a dirigible air ship, a support, a pair of aeroplanes supported by and extending longitudinally of the support, each arranged to extend beyond one side of the support, said pair of aeroplanes being movable toward and away from each other at will, and means operatively related to the aeroplanes for maintaining the equilibrium thereof. 110 115

2. In combination in a dirigible air ship, a support, a pair of aeroplanes supported by and extending longitudinally of the support, each arranged to extend beyond one side of the body, said pair of aeroplanes being movable toward and away from each other at will, and means operatively related to the aeroplanes for maintaining the equilibrium thereof, the said aeroplanes being located above the diametric center of the support. 120 125

3. In combination in a dirigible air ship, a support, a pair of aeroplanes supported by and extending longitudinally of the body, 130

each arranged to extend laterally beyond the support, said pair of aeroplanes being movable toward and away from each other at will, and means operatively related to the 5 aeroplanes for maintaining the equilibrium thereof, said aeroplanes being located above the diametric center of the support.

4. In combination in a dirigible air ship, a tubular body, means for forcing air 10 through the body at a greater rate of speed than the speed of the outside air, a pair of aeroplanes supported by and extending longitudinally of the body, each arranged to extend beyond one side of the body, said 15 pair of aeroplanes being movable toward and away from each other at will, and means operatively related to the aeroplanes for maintaining the equilibrium thereof.

5. In combination in a dirigible air ship, 20 a tubular body, means for forcing the air through the body at a greater rate of speed than the speed of the outside air, a pair of aeroplanes supported by and extending longitudinally of the body, said aeroplanes being 25 adjustable toward and away from each other at will, and counterbalancing means operatively related to the said aeroplanes for maintaining the equilibrium thereof.

6. In combination in a dirigible air ship, 30 a tubular body, means for forcing the air therethrough at a greater rate of speed than the speed of the outside air, a pair of aeroplanes supported by and extending longitudinally of the body, said aeroplanes being 35 adjustable toward and away from each other at will, and weighted arms operatively related to the said aeroplanes for maintaining the equilibrium thereof.

7. An air ship including in combination a 40 support, a pair of aeroplanes supported thereby each comprising sections in pivotal relation to each other, means for adjusting said planes and sections in directions toward and away from the longitudinal axis 45 of the support, and means operatively related to the aeroplanes for counterbalancing said aeroplanes.

8. An air ship including in combination a support, a pair of aeroplanes supported

thereby in pivotal relation to the support 50 and with respect to each other, said aeroplanes comprising sections adjustable transversely with respect to the support, and weighted arms operatively related to the aeroplanes for maintaining the equilibrium 55 thereof.

9. An air ship including in combination a support, a pair of aeroplanes supported thereby, on an axis extending lengthwise of the support and in pivotal relation to the 60 support and with respect to each other, said aeroplanes extending longitudinally with respect to the support and projecting laterally beyond the support and comprising sections adjustable transversely with respect to the 65 support, and a weighted arm operatively related to each of the aeroplanes for maintaining the equilibrium thereof.

10. An air ship including in combination a support, a pair of aeroplanes supported 70 thereby on axes extending lengthwise of the support, and in pivotal relation to the support and with relation to each other, said aeroplanes extending longitudinally of the machine and projecting laterally beyond the 75 support, said aeroplanes each comprising sections adjustable with respect to each other and transversely with respect to the support, and counterbalancing means operatively related to each of the aeroplanes for maintaining the equilibrium thereof.

11. An air ship including in combination a support, a pair of aeroplanes pivotally supported thereby on axes extending lengthwise of the support and in pivotal relation 85 to the support and with relation to each other, said aeroplanes projecting laterally beyond the support, and counterbalancing means operatively related to the aeroplanes for maintaining the equilibrium thereof. 90

In testimony whereof I have signed my name to this specification, in the presence of two subscribing witnesses, on this 26th day of February, A. D. 1907.

ANTHONY R. SILVERSTON.
